FASTENING MEANS.

Application filed January 30, 1926. Serial No. 84,953.

This invention relates to fastening means and particularly to fastening means for hoods of motor vehicles.

The objects of the invention are to provide a fastening means which will be very sturdy and withstand hard usage as well as continued vibration and movement in connection with holding the hood of a motor vehicle closed; to provide a structure wherein a spring action may be employed and a sturdy spring utilized without necessitating such strength of resiliency as to make use impractical; to obtain a uniform tension on the hood; to provide a structure which utilizes parts readily applied and easily manufactured or obtainable on the market; to secure simplicity of construction and operation, and to obtain other advantages and results as may be brought out in the following description.

Referring to the accompanying drawing in which like numerals of reference indicate similar parts throughout the several views;

Figure 1 is a side elevation of a portion of a motor vehicle showing our improved fastening means in place;

Figure 2 is an enlarged view of said fastening means of Figure 1 with portions of the vehicle likewise shown; and

Figure 3 is a sectional view on line 3—3 of Figure 2.

In the specific embodiment of the invention illustrated in said drawing, the reference numeral 1 indicates the motor vehicle in general having a hinged hood 2 which it is desired to retain closed during normal operation of the vehicle. It has been common practice heretofore to provide a spring actuated hook adjacent the front and rear end of the hood which is adapted to engage a suitable catch for retaining the hood closed. A device of that nature utilizes a coil spring which has to be limited as to length and its strength of resiliency cannot exceed a certain amount these limitations having resulted in the devices of that nature proving unsatisfactory and frequently broken.

In carrying out our invention we provide a leaf spring 3 secured at a middle part of itself to a suitable bracket 4 attached to the hood intermediate its front and rear edges. This leaf spring 3 can be made of suitable strength so as to make it almost impossible to break it and yet it will be of sufficient length so its resiliency does not exceed that

which a person is capable of overcoming for releasing and attaching the same in operation. The outer ends of said leaf spring are preferably curled over, as at 5, and in the present disclosure are shown as carrying in 60 said curled ends each a suitable link 6 adapted to engage a hook 7 fast with respect to the vehicle body. The ends of leaf spring 3 are depressed and the links 6 are caught on to hooks 7 thereby holding the hood 2 of the 65 vehicle securely closed but with appropriate resiliency for accommodating normal movement of the hood during use of the vehicle. The securing device is readily released by pressing open the ends of said leaf spring 70 and swinging links 6 out from engagement with the hooks 7.

In order to secure the bracket 4 with assurance that it will not damage the hood, pull loose or apply greater tension on one 75 end of the hood than the other, we deem it advisable to provide a reinforcing bar 8 on the inner side of the hood extending a considerable length and as shown in the drawing substantially the length of the hood. 80 This bar is preferably secured, as by rivets, to the hood at various points, and the bracket 4 preferably is riveted through the hood to the bar.

Obviously detail changes and modifications may be made in the construction and use of our improved fastening means and we do not wish to be understood as limiting ourselves to the exact structure shown except as set forth in the following claims 90

Having thus described our invention, we claim:

1. In combination with a motor vehicle having a hood, a leaf spring secured to said hood at one side thereof and releasably attached to a fixed part of the vehicle at the same side of the vehicle as said leaf spring is attached for securing the hood in closed position.

2. In combination with a motor vehicle having a hood, a leaf spring extending longitudinally of said hood and attached thereto, and means for releasably attaching the end of said leaf spring to fixed part of the vehicle adjacent the hood for retaining said hood closed.

3. In combination with a motor vehicle having a hood, a bracket on said hood, a leaf spring secured at a middle part of itself to 110

said bracket and having its ends free and both ends on the same side of the hood, and means for releasably securing the ends of said leaf spring to a fixed part of the vehicle for holding the hood closed.

4. In combination with a motor vehicle having a hood, a reinforcing bar under the hood, a bracket secured on the outside of

the hood to said reinforcing bar, a leaf spring secured at a middle part of itself to said bracket and carrying links at its outer free ends, and hooks carried by the vehicle adapted to be engaged by said links for resiliently holding the hood closed.

HERSCHEL A. BENEDICT.
